Letters Patent No. 80,848, dated August 11, 1868.

MOVEMENT IN APPARATUS FOR SETTING AXLES OF WHEELS.

The Schedule referred to in these Letters Patent and making part of the same.

TO WHOM IT MAY CONCERN:

Be it known that I, SAMUEL WOODHULL, of Linden, in the county of Genesee, and State of Michigan, have invented a new and useful Improvement in an Apparatus for Obtaining the Pitch and Gather of Wagon-Axles; and I do declare that the following is a true and accurate description thereof, reference being had to the accompanying drawings, and to the letters of reference marked thereon, and being a part of this specification.

The object of this invention is to construct an apparatus by which the pitch of the arm of an axle may be readily obtained, without the operator being obliged to make calculations which are sometimes wrong, and productive of great loss of time and labor.

In order to accomplish this end, I take a straight bar, A, of any proper length, which is provided at one end with transverse bar B, while the other end is provided with adjustable transverse bar D. I provide two other bars, E, longer than the bar A, to which they are attached, one upon the top, and one upon the under side thereof, by being pivoted at F. These bars are properly graduated, and are provided with slots, G, and set-screws, H, by means of which they are adjusted and held in place. Attached to the ends of the bar D, and pivoted thereto, are the parallel bars I and J, whose outer sides are directly upon a line with the ends of the transverse bar B. These bars I and J are pivoted at their other ends to short arms, K, which are pivoted at their opposite ends to the ends of the bars E. When the bars F are perfectly parallel with the bar A, the outer faces of the bars I and J are also perfectly parallel with each other.

In using this apparatus, the following directions must be observed:

First, lay the gauge down with the pivoted ends of the levers to your right hand.

Second, obtain the "dish" of your wheel by laying a straight-edge across the rim, at the centre of its diameter.

Third, find the figure on one of the bars E that corresponds to half the height of your wheel, in the small scale.

Fourth, move the bar E over from you, at the figure just found, just what your wheel dishes, and fasten it by set-screw H.

Fifth, now find how much your arm tapers, by measuring it close up to the swell and at the point. Get also the length from where you measured to the point. Then find the figure in the large scale representing the length of your arm, and at that point move the bar E back towards you, just the taper of the arm.

Sixth, then you are ready to fit up the under side of your arm, and get an accurate pitch thereto for a plumb spoke.

I do not claim broadly an axle-gauge, such as is shown in the patent to William E. Barnberger, dated November 15, 1859; but

What I claim as my invention, and desire to secure by Letters Patent, is—
The arms K, in an axle-gauge, constructed as herein described and shown.
